UNITED STATES PATENT OFFICE.

HAROLD H. TURNER, OF CHICAGO, ILLINOIS.

MOTOR OR ENGINE.

1,275,502.

Specification of Letters Patent. Patented Aug. 13, 1918.

Application filed September 22, 1915. Serial No. 52,017.

To all whom it may concern:

Be it known that I, HAROLD H. TURNER, a citizen of the United States, residing at Chicago, in the county of Cook and State 5 of Illinois, have invented certain new and useful Improvements in Motors or Engines, of which the following is a specification.

My invention relates to prime movers of a type in which explosions of charges of carbureted air or equivalent explosive vapors act upon a body of liquid, such as mercury, to intermittently drive it through a closed circuit of chambers and passages, in the course of which it is directed against the 15 blades of a turbine wheel to turn it and supply power; suitable provision of course being made for exhausting the spent products of combustion. The general object of my invention is the production and embodiment 20 of this novel type of engine in a practical and efficient form, to which end I have devised the particular mechanical construction and arrangement of parts shown in the drawings and hereinafter described, and 25 which exhibit incidental features of novelty and utility which will hereinafter appear and are more particularly pointed out in the appended claims.

I have illustrated my invention as embodied in two forms of engine, differing somewhat in arrangement and construction, but having the same mode of operation; and it will be understood that my invention embraces all modifications and variations of 35 form which come within the scope of my claims and do not depart substantially from the principle thereof.

Of the drawings, Figure 1 is a plan view of the form of engine first to be described; 40 Fig. 2 is a side elevation thereof; Fig. 3 is an end view looking from the right, as viewed in Figs. 1 and 2; Fig. 4 is a section on the line 4—4 of Fig. 1; Fig. 5 is a detail of the spark plug arrangement used at the top of 45 the explosion chambers; Fig. 6 is a vertical section through the distributing valve at right angles to its axis showing the arrangement of parts and passages; Fig. 7 is a section of the same taken through its axis; Fig. 50 8 is a vertical section of a modified form of motor, taken on the line 8—8 of Fig. 9; Fig. 9 is a front view of such modified form; Fig. 10 is a central vertical section of the motion looking in the direction of the 55 rows 10—10; Fig. 11 a section in the same plane, but looking in the direction of the

arrow 11—11, and with the distributing valve in a different position; and Fig. 12 a detail of a check valve at the outlet of a pipe connecting the collecting and pressure chambers of the engine, and taken on the line 12—12 of Fig. 10.

The same letters of reference indicate the same parts in all the figures of the drawings.

Referring first to the form of engine shown in Figs. 1 to 5, the frame and casing of the engine may conveniently be formed of two vertically arranged hollow castings 1 and 2, respectively closed at their rear sides 60 by the plates 3 and 4. To these castings are bolted or otherwise secured transversely arranged hollow castings 5 and 6, formed with outwardly extending radiating flanges and respectively inclosing the explosion chambers 65 G and H. The front casting or casing and frame member 1 is formed with a pressure chamber C, arranged beneath the explosion chamber G, and a collecting chamber D, beneath the explosion chamber H; 70 and also with a turbine chamber, within which is arranged the turbine wheel 7 equipped with the blades 8 and secured to the rotatable motor shaft 9 extending through and journaled in bearings on the castings 1 and 2 and cover plates 3 and 4. The bottom of the turbine chamber opens or exhausts into the collecting chamber D through an opening controlled by the check valve 10. The rear casting 2 is similarly formed, with a 75 pressure chamber A beneath the explosion chamber G and a collecting chamber B beneath the explosion chamber H, and with a 80 turbine chamber in which is arranged a turbine wheel similar to the turbine wheel 7 and 85 also mounted on the shaft 9. The bottom of this turbine chamber opens into the collecting chamber B, and passage therethrough is governed by a check valve 10 similar to the valve 10 and lying immediately back of 90 such valve as viewed in Fig. 4. A large port G' affords free communication between the combustion chamber G and the pressure chamber A, and a similar port H' affords 95 like communication between the combustion chamber H and pressure chamber B. A pipe J provides free communication between the explosion chamber G and the collecting chamber D, and a pipe I similarly provides 100 free communication between the explosion chamber H and the collecting chamber C.

A pipe O forming a mercury conduit

leads from the rear passage chamber A to a discharge opening near the top of the rear turbine chamber, and a simliar pipe Q leads from the bottom of the front pressure chamber C to the top of the front turbine chamber.

It will be observed that the chambers and passages thus far described constitute two separate passageways for the circulation of 10 two different charges of bodies of mercury, one on each side of the engine, one of which bodies acts on one turbine wheel and the other on the other, both wheels being secured to the same motor shaft. By means 15 which will hereinafter be described the body of mercury on one side of the motor is driven, by explosions in the chamber G, from the pressure chamber A through the pipe O and rear turbine passages and 20 through the check valve 10^a into the collecting chamber B; and, on the other side, by explosions in the chamber H alternating with the explosions in the chamber G, the other body of mercury is driven from the 25 chamber C through the pipe Q and front turbine passages into the collecting chamber D; the mercury driven from such chamber C into the chamber D at one explosion being forced at the next explosion (in the opposite explosion chamber), back into chamber C through a port governed by the check valve 11, and the mercury being returned 30 from the chamber B to the chamber A through an opening controlled by a similar 35 check valve 11^a in the same manner. This check valve lies directly beyond said valve 11 as viewed in Fig. 4, as indicated by the dotted leader line.

The apparatus used for producing explosions alternately in the chambers G and H of the motor comprises a carbureete 12, through which, by the action of the pump 13, a suitable hydrocarbon is drawn in from a supply tank (not shown) and air is drawn 45 in through a regulating valve 14, the carbureted mixture being brought by the action of the pump to a high pressure in the vapor reservoir 15;—a rotary distributing valve 16 by which the explosive vapor from such 50 reservoir is admitted alternately into the combustion chambers; and an electric sparking system for exploding the charges of vapor.

For reciprocating the piston of the pump 55 an eccentric 17 fixed to the motor shaft is employed, while a small pinion 18 fixed on said shaft, meshing with a larger pinion 19 on the shaft of the distributing valve serves to rotate such valve; the gearing of the 60 parts being such that the piston of the pump will be reciprocated a considerable number of times to each revolution of the distributor, thus maintaining a considerable degree of pressure in the vapor reservoir. The casing 65 20 of the distributor is formed with a

port P' at the end of the inlet pipe P leading from the vapor reservoir thereto, and is also formed with a port N' communicating with the end of a pipe N leading to the combustion chamber G, and a port K' communicating with the end of a pipe K leading to the combustion chamber H. Through a branch or manifold passage the pipe K also communicates with a port K² back of and in the same axial plane as the port N'; and the 70 pipe N in a like manner communicates with a port N² in the same axial plane as the port K'. The ports N' and N² are in one radial plane, and the ports K' and K² are in a different and parallel plane, while the 75 port P' and an exhaust port 23 are broad enough to overlap both planes. The inlet passage terminating in the port P', and the exhaust passage 23, however, are so formed as not to intersect any of the other passages 80 of the casing. The distributor is provided with bridging passages 21 and 22 which are arranged to place the port P' alternately in communication with the ports N' and K² so that the passage 21 will begin to supply explosive vapor to the pipe N and connected 85 chambers from the vapor reservoir 15, under the pressure therein caused by the pump, when the passage 22 places the pipe K and connected chambers in communication 90 through the port K' with the exhaust port and passage 23. The charge of vapor which is thus caused to pass into the combustion chamber G is exploded immedately after the closing of the port P' by a spark plug 100 located at the top of the chamber, at the entrance of the pipe thereinto. Upon the rotation of the valve through an arc of one hundred and eighty degrees the connections are reversed, and the explosion chamber H 105 will be charged and exploded in the same manner. This spark plug may be of the form shown in Fig. 5, in which an insulated section 24 at the end of the pipe K, forming one electrode, is electrically connected with 110 one terminal of the battery through a contact breaking switch, while a second electrode 25 is formed upon the plug member 26 which is screwed directly into a screw threaded bore at the top of the chamber, 115 the other terminal of the battery being connected with the engine frame, which thus serves as a ground.

The spark may be caused by any suitable form of switch geared to a moving part of 120 the engine and arranged to open and close the electric circuit to produce a spark at the proper time. In Fig. 7, I have illustrated a suitable switch for the purpose forming part of the rotary distributor structure. In 125 this switch an insulated metal spring 27 carried by the distributor casing and in electrical communication with one terminal of the battery is in constant contact with an insulated ring 28 supported by a fiber plate 29 130

secured to the body of the rotary distributor 16. A laterally extending roller carried by this ring 28 co-operates with two insulated spring contact members 30, fixed in the casing of the distributor, one of these contacts 30 being connected to the spark plug member 24 at the top of the explosion chamber G, and the other to the similar member at the top of the chamber H.

10 From the description already given the operation of my new motor will be readily understood. Assuming, as a point for beginning a description of the cycle of action of the motor, that the pressure chamber A 15 and collecting chamber D are filled with mercury, the rotation of the distributor permits the explosion chamber G to fill with vapor, compressing the products of explosion remaining therein and which at the time 20 were at atmospheric pressure and forcing them to the farther parts of the chambers A and D, and also opens the explosion chamber H and connected chambers B and C to exhaust. As soon as the distributor closes 25 the port P, a spark ignites the charge, and the high pressure created by the explosion extends to the chambers A and D, driving the mercury from the chamber D into the chamber C, as heretofore described, the 30 check valves 10^a and 11^a preventing escape of the contents of the chambers in a reverse direction at a succeeding stage. The space in the chambers B and C and explosion chamber H filled with the products of a 35 previous explosion in the last mentioned chamber are driven out through the pipe K and exhaust port of the distributor.

In Figs. 8, 9, 10 and 11 I have illustrated 40 an upright or vertical form of motor embodying my invention in which the pressure chambers from which the mercury is driven through the turbine wheels are arranged at the top, while the collecting chambers are arranged at the bottom; and in which there is 45 no distinct combustion chamber; the explosive vapor being driven into the top portions of the pressure and collecting chambers and there exploded, preferably by separate sparks, one in each chamber.

50 In this form of engine, the explosion chambers 31 and 32 at the top of the engine, which are at once the combustion and pressure chambers, communicate with the collecting chambers 34 and 33, respectively, on opposite sides of the engine at the bottom thereof, through the pipes 35 and 36. These pipes respectively communicate through branch pipes 37 and 38 with a rotary distributor which is practically identical with 55 that of the form of engine first described, and which is connected through a supply pipe 45 with a source of explosive vapor. A check valve 39 is placed at the exit of the turbine passage interposed between the pressure chamber 31 and collecting chamber 34

where it enters such last mentioned chamber; and a similar valve is placed at the exit of the other turbine passage, between the chambers 32 and 33. A pipe 40 leads from the bottom of the collecting chamber 34 to 70 the top of the pressure chamber 31, a check valve (see Fig. 12) being placed at the point where it enters such chamber, and a similar pipe 42, provided with a similar check valve, leads from the bottom of the chamber 33 to 75 the top of the chamber 32. A passage 43 formed in the casing leads from the bottom of the pressure chamber to the top of the turbine casing, and a similar passage leads from the bottom of the other pressure chamber to the top of the other turbine.

As in the case of the motor first described the apparatus for igniting the explosive vapor may be constructed as a part of the rotary distributing valve structure, but 85 preferably sparks should be made simultaneously in the pressure chamber 31, and collecting chamber 34 at one time, and in the chambers 32 and 33 at the alternate intervals. However, this simultaneous sparking in both chambers is not essential, as the explosive vapor in the pipes 35 and 36 will constitute rapid and effective fuses for causing "back firing" from an explosion in only 90 one of two connected chambers to the other. 95 The mercury will on the one side of the motor be forced successively at one explosion from the collecting chamber 34 through the pipe 40 into the pressure chamber 32 and at the next explosion in the chamber 100 32 through the passage 43 through the turbine, collecting again in the chamber 34; and on the other side from the chamber 33 into the chamber 31, and from the chamber 31 through the other turbine back into the 105 chamber 33; the stages on the opposite sides alternating. When an explosion occurs in the chambers 31 and 34 the products of combustion in the chambers 32 and 33 escape through pipes 35 and 37 and communicating 110 passages of the distributor leading to the exhaust passage and port 44 and when the explosion occurs in the chambers 32 and 33 the products in chambers 31 and 34 escape through pipes 36 and 38 and communicating 115 passages to said exhaust port.

While mercury is the liquid most perfectly adapted for use in such engines as those above described, it will be understood that other liquids having a very high vaporizing point such as certain mineral oils may be used in engines having the same mode of operation, and also embodying my invention.

I claim:

1. A motor of the character described and 125 including a casing formed with a turbine chamber having inlet and outlet openings, a turbine wheel within said chamber arranged to be operated by a liquid flowing therethrough, a pressure chamber adapted to re- 130

- ceive a body of liquid and having a bottom opening, a passage connecting said bottom opening and the inlet opening of the turbine chamber, a return passage connecting 5 said outlet opening and the pressure chamber, a valve governing communication through said outlet opening, a valve governing communication between said return passage and said pressure chamber, means for 10 periodically igniting charges of an explosive in the pressure chamber, and means for synchronously relieving pressure in said turbine chamber.
2. A motor of the character described and 15 including a casing formed with a turbine chamber having inlet and outlet openings, a turbine wheel within said chamber arranged to be operated by a liquid flowing therethrough, a pressure chamber adapted 20 to receive a body of liquid and having a bottom opening, a passage connecting said bottom opening and the inlet opening of the turbine chamber, a return passage connecting said outlet opening and the pressure 25 chamber, a valve governing communication through said outlet opening, a check valve governing said outlet opening, a check valve between said return passage and said pressure chamber, means for periodically igniting charges of explosive in the pressure 30 chamber, and means for synchronously relieving pressure in said return passage and turbine chamber.
3. A motor of the character described and 35 including a casing formed with a turbine chamber having inlet and outlet openings, a turbine wheel within said chamber arranged to be operated by a liquid flowing therethrough, a pressure chamber adapted 40 to receive a body of liquid and having a bottom opening communicating with the inlet opening of the turbine chamber, a collecting chamber connecting with the outlet opening of the turbine chamber and having 45 valve-governed communication with the pressure chamber, means for periodically exploding charges of an explosive in the pressure chamber to drive the body of liquid therefrom through the turbine passages into 50 the collecting chamber, and means for expelling such liquid from the collecting chamber again into the pressure chamber in the intervals between the explosions in such pressure chamber.
4. A motor of the character described and 55 including a casing formed with a turbine chamber having inlet and outlet openings, a turbine wheel within said chamber arranged to be operated by a liquid flowing 60 therethrough, a pressure chamber adapted to receive a body of liquid and having a bottom opening communicating with the inlet opening of the turbine chamber, a collecting chamber having valve-governed communication with the outlet opening of the 65 turbine chamber and also having valve-governed communication with the pressure chamber, means for periodically exploding charges of an explosive in the pressure chamber to drive the body of liquid therefrom through the turbine passages into the collecting chamber, and gaseous fluid pressure means for expelling such liquid from the collecting chamber again into the pressure chamber in the intervals between the 70 explosions in such chamber.
5. A motor of the character described and including a casing formed with a turbine chamber having inlet and outlet openings, a turbine wheel within said chamber arranged 75 to be operated by a liquid flowing therethrough, a pressure chamber adapted to receive a body of liquid and having a bottom opening communicating with the inlet opening of the turbine chamber, a collecting chamber having valve-governed communication with the outlet opening of the turbine chamber and also having valve-governed communication with the pressure chamber, means for periodically exploding 80 charges of an explosive in the pressure chamber to drive the body of liquid therefrom through the turbine passages into the collecting chamber, and means for periodically 85 exploding charges of an explosive in said collecting chamber to expel such liquid therefrom back into said pressure chamber alternately with the explosions in such pressure chamber.
6. A motor of the character described and 90 including a casing formed with a turbine chamber having inlet and outlet openings, a turbine wheel within said chamber arranged to be operated by a liquid flowing 95 therethrough, a pressure chamber adapted to receive a body of liquid and having a bottom opening communicating with the inlet opening of the turbine chamber, a collecting chamber communicating with the outlet opening of the turbine chamber, a check valve governing such communication, a check-valve-governed passage between said collecting chamber and said pressure chamber, means for exploding charges of explosive gas alternately in said pressure chamber and said collecting chamber to drive the 100 body of liquid from the former chamber through the turbine passages into the latter chamber, and then again into the first mentioned chamber, and valve-governed 105 passages and ports for exhausting the products of explosion.
7. A motor of the character described and including a casing formed with a turbine chamber having inlet and outlet openings, a turbine wheel within said chamber arranged 110 to be operated by a liquid flowing therethrough, a pressure chamber adapted to receive a body of liquid and having a bottom opening communicating with the inlet open- 115

- ing of the turbine chamber, a collecting chamber communicating with the outlet opening of the turbine chamber, a check valve governing such communication, a 5 check-valve-governed passage between said collecting chamber and said pressure chamber, a passage communicating with said pressure chamber for supplying it with charges of explosive gas and exhausting the 10 products of combustion therefrom, a second passage communicating with said collecting chamber for supplying it with charges of explosive vapor and exhausting the products of combustion therefrom, a source for 15 supplying gas under pressure, valve means for placing one of said passages in connection with said source and then shutting it off and simultaneously placing the other passage in exhaust condition, such valve being 20 arranged to establish such connections with the two passages in alternation, and igniting means for exploding the charges while shut off from the source of gas supply.
8. A motor of the character described and 25 including a casing formed with a turbine chamber having inlet and outlet openings, a turbine wheel arranged within said chamber and adapted to be operated by a liquid, a passage connecting said openings and pro- 30 viding with the turbine passages of the motor a passageway for the flow of a body of liquid in a closed circuit therethrough, and means for driving such liquid through said passageway.
- 35 9. A motor of the character described and including a casing formed with a turbine chamber having inlet and outlet openings, a turbine wheel arranged within said chamber and adapted to be operated by a liquid, a pressure chamber and passages communi- 40 cating with said opening and providing with the turbine passages of the motor a passageway for the flow of a body of liquid in a closed circuit therethrough, means for 45 periodically discharging charges of explosive gas in said pressure chamber to drive the body of liquid therefrom through the turbine passages; and means for exhausting the products of combustion.
- 50 10. A motor of the character described and including a casing formed with a turbine chamber having inlet and outlet openings, a turbine wheel arranged within said chamber and adapted to be operated by a 55 liquid, a pressure chamber having a passage for the flow of liquid from its bottom to the inlet opening of the turbine chamber, a passage for the flow of liquid from the outlet opening of the turbine chamber back 60 into the pressure chamber, a body of liquid arranged to circulate through said chambers and passages, means for periodically discharging charges of explosive vapor in said pressure chamber to drive the body of liquid 65 therefrom through the turbine passages, and means for exhausting the products of combustion.
11. A motor of the character described and including a casing formed with a turbine chamber having inlet and outlet openings, a turbine wheel arranged within said chamber and adapted to be operated by a liquid, a pressure chamber having a passage for the flow of liquid from its bottom to the inlet opening of the turbine chamber, a 70 collecting chamber communicating with said outlet opening and with said pressure chamber, a body of liquid arranged to circulate through said chambers and passages, and means for periodically exploding charges 75 of explosive vapor to successively drive said body of liquid from said pressure chamber through the turbine passages into said collecting chamber and from said collecting chamber back into said pressure chamber.
12. A motor of the character described and comprising frame and casing members formed at opposite sides with two turbine chambers having inlet and outlet openings, two turbine wheels operatively connected to 90 a common driving member, two pressure chambers at opposite sides of the motor respectively, having passages from their bottoms to the inlet openings of the two turbine chambers, two passages respectively connecting said two turbine chambers through their outlet openings and two pressure chambers, two bodies of liquid arranged to circulate independently in the chambers and 95 passages at opposite sides of the motor, and means for alternately discharging charges of explosive vapor in the two pressure chambers to drive said bodies of liquid therefrom through the respective turbine passages.
13. A motor of the character described and comprising frame and casing members formed at opposite sides with two turbine chambers having inlet and outlet openings, two turbine wheels operatively connected to 100 a common driving member, two pressure chambers at opposite sides of the motor respectively, having passages from their bottoms to the inlet openings of the two turbine chambers, two collecting chambers at 105 opposite sides of the motor communicating respectively with the outlet openings of the turbine chambers, and with the two pressure chambers on the same side, the pressure chamber on one side of the motor being 110 in free communication with the collecting chamber on the other side and vice versa, means for periodically discharging charges of explosive vapor to produce high pressure simultaneously in the pressure chamber on 115 one side and the collecting chamber on the other side of the motor, and vice versa, in alternation, to drive the bodies of fluid at opposite sides of the motor successively from the pressure chamber on a given side 120
- 125
- 130

through the turbine passages into the collecting chamber on that side and then from the collecting chamber again into the pressure chamber, and means for venting the 5 products of combustion.

14. A motor of the character described and comprising frame and casing members formed at opposite sides with two turbine chambers having inlet and outlet openings, 10 two turbine wheels operatively connected to a common driving member, two pressure chambers at opposite sides of the motor respectively, having passages from their bottoms to the inlet openings of the two turbine chambers, two collecting chambers at 15 opposite sides of the motor communicating respectively with the outlet openings of the turbine chambers, and with the two pressure chambers on the same side, the pressure chamber on one side of the motor being in 20 free communication with the collecting chamber on the other side and vice versa, a source for supplying gas and valve means for periodically supplying gas to one pressure chamber and connected collecting chamber 25 and then shutting it off and simultaneously placing the other pressure chamber and connected collecting chamber in exhaust connection, such valve means being arranged 30 to establish such connections reversely in alternation, and igniting means for exploding the charges while shut off from the source of gas supply.

15. A motor of the character described 35 and including a casing formed with a turbine chamber having inlet and outlet openings, a turbine wheel within said chamber arranged to be operated by a liquid flowing therethrough, a combustion chamber, a pressure chamber in free communication therewith and adapted to receive a body of liquid 40 and having a bottom opening communicating with the inlet of the turbine chamber, a collecting chamber at the outlet of the turbine chamber and communicating with the pressure chamber, means for introducing charges of explosive vapor into said combustion chamber, and means for exploding such charges to drive the body of liquid 45

from the pressure chamber through the turbine chamber into the collecting chamber.

16. A motor of the character described and comprising frame and casing members formed at opposite sides with two turbine chambers having inlet and outlet openings, 50 two turbine wheels operatively connected to a common driving member, two combustion chambers at opposite sides of the motor, two pressure chambers respectively in free communication with said two combustion chambers and respectively having passages leading from their bottoms to the inlets to the two turbine chambers, two collecting chambers at opposite sides of the motor communicating respectively with the outlets of the 55 two turbine chambers and with the two pressure chambers on the same side, the combustion chamber on one side of the motor being arranged in free communication with the collecting chamber on the other side, and 60 vice versa, means for introducing charges of explosive vapor into said combustion chambers alternately, means for exploding said charges, and means for venting the 65 products of combustion.

17. A motor of the character described comprising a frame and casing formed with a passage way for the circulation of a body of liquid and including a turbine chamber and an explosion chamber, a body of liquid 70 in said passageway, an electric circuit including an igniter arranged in said explosion chamber, a reservoir for explosive vapor, a pump arranged to pump explosive vapor 75 into said reservoir and bring it to high pressure, a distributing valve for admitting charges of gas periodically into said explosion chamber, and a switch contact member mounted on said valve and coöperating with a fixed switch contact member to 80 interrupt the electric circuit and produce explosions in said explosion chamber to drive the body of fluid through said turbine chamber.
